UNITED STATES PATENT OFFICE.

ANDREW WALTER SCOTT, JR., OF VENICE, CALIFORNIA.

DESIGN FOR A TOY GOOSE.

Application filed May 6, 1924. Serial No. 9,492. Term of patent 3½ years.

To all whom it may concern:

Be it known that I, ANDREW WALTER SCOTT, JR., a citizen of the United States, residing at Venice, in the county of Los Angeles and State of California, have invented a new, original, and ornamental Design for Toy Goose, of which the following is a specification, reference being had to the accompanying drawing, forming part thereof.

In the drawings:

Figure 1 is a perspective view of a goose, showing my new design; and

Figure 2 is a front elevation of a goose, showing my new design.

I claim:

The ornamental design for a toy goose, as shown.

ANDREW WALTER SCOTT, JR.
